(57) **CLAIM**

We claim the ornamental design for a portable monitoring device, as shown and described.

DESCRIPTION

FIG. 1 is a perspective view of a portable monitoring device showing our new design;

FIG. 2 is a front view thereof;

FIG. 3 is a rear view thereof;

FIG. 4 is a top plan view thereof;

FIG. 5 is a bottom plan view thereof;

FIG. 6 is an enlarged left end view thereof; and,

FIG. 7 is an enlarged right end view thereof.

The portions of the monitoring device depicted by means of broken lines in the drawing figures form no part of the claimed design.
